UNITED STATES PATENT OFFICE.

BENJAMIN F. CAYFORD, OF SKOWHEGAN, MAINE.

RUNNER ATTACHMENT FOR TRACK-SULKIES.

1,047,745.

Specification of Letters Patent. Patented Dec. 17, 1912.

Application filed February 9, 1912. Serial No. 676,683.

To all whom it may concern:

Be it known that I, BENJAMIN F. CAYFORD, a citizen of the United States, residing at Skowhegan, in the county of Somerset and State of Maine, have invented certain new and useful Improvements in Runner Attachments for Track-Sulkies; and I do hereby declare the following to be a full, clear, and exact description of the invention, such as will enable others skilled in the art to which it appertains to make and use the same.

This invention relates to improvements in runner attachments for track sulkies of that type wherein the ordinary track wheels are held to the sulky through the medium of a displaceable bolt spanning the space between the forked wheel carrying members.

The main and primary object of the present invention is the provision of a runner attachment of the character described, by which the modern type of track sulkies may be readily converted from a wheeled vehicle into a runner supported vehicle, thereby adapting the same for ice racing as well as for racing under the ordinary conditions.

A further object of the present invention is the provision of a runner attachment, the construction of which is such that the runners are preserved in parallelism with each other so as to insure proper tracking of the sulky and to include with the construction of the attachment simple and efficient means for rigidly supporting the same upon the sulky.

While the invention is primarily intended for use with the light-frame sulky of the modern type it is also capable of use with other types of road sulkies and carts, so that its use is not limited to the modern track sulky which is now commonly used.

Having these general objects in view the invention consists substantially in the novel construction, combination and arrangement of parts hereinafter fully described, illustrated in the accompanying drawing, and pointed out in the appended claim.

In the drawings: Figure 1 is a side elevation of a track sulky equipped with a runner attachment embodying the present invention. Fig. 2 is a detail perspective view of the runner attachment removed from the sulky. Fig. 3 is a top plan view of the supporting plate. Fig. 4 is a fragmentary end elevation, partially in section, of one of the

forked members of the sulky with the runner applied thereto.

Referring in detail to the accompanying drawings, the numeral 10 designates the frame of a track sulky. As these modern sulkies are commonly constructed they include depending forked members 11 provided with forwardly extending braces 12, the rear ends of the braces being connected to the lower ends of the forked members 11, while the forward ends of said braces are connected to the shafts 13 of the sulky. The road wheels are held within the forked members 11 by means of bolts 14, and it is the purpose of the present invention to utilize these bolts as the securing means for connecting the runner attachments to the sulky frame.

As clearly illustrated in Figs. 1 and 2, the runner attachment constituting the present invention comprises a shoe 15, the forward end of which is turned upwardly in the usual manner, and rising from the shoe 15, at a point substantially midway its ends, is a substantially U-shaped standard 16, the lower end of which is secured as by riveting to the shoe 15. The upper ends of the standard 16 being separated, a space is provided thereat and fitting within the upper ends of the standard 16 is a supporting plate 17, the sides of which are provided with upwardly extending parallel ears 18 which are perforated and designed to receive the bolt 14. At the under side of the supporting plate 17 is a brace 19, the ends of which are inclined downwardly to the shoe 15 and are preferably riveted thereto. It will thus be seen that the supporting plate 17 is sustained by the middle portion of the brace 19 and lateral movement of said supporting plate is likewise prevented by the sides of the vertical standard 16.

As a further means of bracing the structure, an inverted U-shaped strap 20 is arranged in the lower end of the standard 16, the extremities of said strap being also secured to the shoe 15 at the front and rear sides of the standard 16.

Seated upon the ears 18 is a securing clip 21 of inverted U-shape, the extremities of said clip being perforated and receiving the bolt 14, and connected to said clip 21 is a brace 22, which extends upwardly within the forwardly extending brace 12 of the sulky frame, the upper end of the brace 22 being 110

provided with an attaching clip 23 which detachably engages the upper end of the brace 12. The function of the brace 22 is to impart rigidity to the runner attachment and 5 to preserve the same in parallelism with the runner attachment at the opposite side of the sulky. In doing this, however, the shoe 15 is free to rotate upon the bolt 14 as its 10 axis and thus to rise and fall with the inequalities of the road bed but without disturbing the parallel relation previously referred to.

As a further means of guiding the forward end of the shoe 15 a strap 24 is employed, said strap being connected to the forward end of the shoe 15 and also to the sulky frame as at 25.

When it is desired to equip a sulky with the herein described runner attachment the 20 ordinary road wheels are removed by properly displacing the bolt 14 at each side of the sulky. When this has been effected the herein-described runner is introduced between the lower end of the forked members 25 11 of the sulky frame, the clip 21 being positioned so that its perforated portions will register with the perforated ears 18 of the supporting plate 17. The bolt 14 is now passed through the perforated ears 18, the 30 clip 21 and the forked members 11 of the frame and the upper end of the brace 22 is attached by its clip 23 to the brace 12 of said frame. The strap 24 when employed is also attached in the manner as previously 35 described.

With the parts adjusted as stated it will be seen that the runner is free to oscillate upon the bolt 14 but by means of the brace 22 it is held rigid against lateral movement so that both runners are always preserved 40 in proper parallel lines and under these conditions it will be understood that the sulky may be used for ice racing without liability of derangement of the runners.

Having thus described the invention, what 45 is claimed as new, and desired to be secured by Letters Patent, is:

A runner attachment for sulky frames comprising a shoe, a substantially U-shaped standard rising therefrom, a supporting 50 plate fitted between the sides of said standard and provided with parallel perforated ears, a brace arranged at the under side of said supporting plate and having its ends connected to said shoe for supporting said 55 plate in relation to said shoe, a bolt passing through the sides of the U-shaped standard, a clip 21 connected to said bolt and a second brace 22 connected at its lower extremity to said clip 21 and removably attached to the 60 sulky frame to furnish additional rigidity to said frame and preserve the parallelism of the runners.

In testimony whereof I affix my signature in presence of two witnesses.

BENJAMIN F. CAYFORD.
